UNITED STATES PATENT OFFICE.

MICHAEL MULLINS, OF TULSA, OKLAHOMA.

WEATHERPROOFING FOR WINDOW CASINGS, ETC.

Application filed March 6, 1928. Serial No. 259,527.

This invention relates to improvements in means for sealing the voids and crevices left in building constructions by application of the corner finishing strips and casing strips 5 of window and door structures upon drop sidings.

The primary object of this invention is the provision of an improved guard which may be applied to the outer edges of casing 10 and finishing strips over drop siding of building constructions, for the purpose of sealing the voids between the boards placed over the drop siding, without alteration to the siding or structural alteration to the 15 siding or finishing strip pieces, and thereby providing an improved building construction which keeps out rain, wind, and the like, rendering the building weather proof to a greater degree, and also rendering the 20 building more sanitary in that dirt cannot collect in such voids or crevices, and as the voids are sealed preventing spiders and insects from using the same for housing or breeding purposes.

25 A further object of this invention is the provision of improved guard or weather stripping which may be used to seal the voids ordinarily appearing under strips placed over drop siding of building constructions; the improved guard means consisting of fillets which may be adjusted to the spacing of the siding.

Other objects and advantages of this invention will be apparent during the course 35 of the following detailed description.

In the accompanying drawing, forming a part of this specification, and wherein similar reference characters designate corresponding parts thruout the several views.

40 Figure 1 is a perspective view showing the application of the improved guard or weather strip construction at the edging of a finishing or casing piece over drop siding, to seal the voids which ordinarily are exposed beneath the finishing or casing piece.

45 Figure 2 is a vertical sectional view taken thru siding as applied to sheathing or the like, showing the details of the improved guard or weather strip construction, and its adjustable nature.

50 Figure 3 is a sectional view taken substantially on the line 3—3 of Figure 2.

Figure 4 is a perspective view of one of the guard fillets, a number of which may be used along a finishing or casing piece to in-

dividually seal the voids in front of the drop siding.

Figure 5 is a fragmentary perspective view of a portion of the improved guard strip construction, adapted to be applied 60 along the edge of a finishing or casing piece to cover the plurality of guard plates also the part of the guard strip construction.

Figure 6 is a modified form of the guard strip construction, showing the formation 65 thereof to a different shape of drop siding than that illustrated in Figure 2, but containing salient features embodied in the form illustrated in Figure 2.

In the drawing, wherein for the purpose of illustration are shown several forms of the improved guard or weather strip construction of the class mentioned, the letter A may generally designate a building 70 construction, which may consist of sheathing B having conventional drop siding C or D of any approved nature applied thereto. Finishing or casing pieces or uprights F may be applied over the drop siding C and 75 D, as is well understood in the art, in connection with window and door casing constructions, and at the corners of building constructions, which are to be finished off. As is well understood in the art voids are 80 ordinarily provided beneath the casing structures of the drop siding and finishing or casing pieces. In order to seal these I provide my improved guard or weather strip construction G or G', for the forms of 85 drop siding C and D respectively, and both of which guard or weather strip constructions G and G' embody the same inventive 90 features.

The drop siding C is of the lap type, and 95 the lower margin of one horizontal siding strip 10 overlaps the upper end of the next lowermost siding strip 11, and so on downwardly along the building construction; the outer faces of the siding strips 10 and 11 100 being acutely inclined to a vertical plane, as is the ordinary construction of drop siding. When the finishing or casing pieces F, which are ordinarily upright, are applied to their proper positions over the drop siding, the rear surface 12 abuts the outermost 105 projecting edges of the drop siding and leave substantially triangular horizontally shaped voids between the outer surface of the siding and the rear of the casing or finishing piece 110.

F, and these voids are ordinarily open at a side edge of the strip F. The same holds true for the type of drop siding D illustrated in Figure 6, which is the overlap bevel 5 type, having outer faces 20 of the siding strips 21 thereof acutely inclined to the vertical and producing the void effect in connection with the finishing or casing piece F. In some cases the drop siding strips do 10 not overlap to the same extent, and hence the provision of a weather strip to seal the void mentioned is not an easy problem to solve in a practical manner. It has been proposed in some cases to provide a straight 15 guard strip and groove the drop siding along the edge of the finishing or casing piece and insert this guard strip in the groove to seal the voids. This is an expensive operation, necessitating the cutting of 20 all of the drop siding vertically along the edge of the finishing or casing piece where the voids open. With my improved guard or weather stripping construction G and G', for this particular use, I do not need to alter 25 the construction of the drop siding nor provide any special cuttings or other operations upon either the drop siding or the finishing or casing pieces.

Referring to the improved guard and 30 weather stripping constructions G and G', the same embody the same arrangement of parts, and the same numerals have been applied to the constructions G and G' in so far as applicable. Each of these guard strip 35 constructions include a plurality of fillet plates 30, preferably formed of some non-rusting or non-corroding metal, such as zinc, or which may be of any approved alloy. The fillets 30 are adapted to take 40 care of but a single void opening, altho in the form of drop siding illustrated in Figure 2 it is entirely feasible to join several of the fillet plates together and stamp the same integral for covering a plurality of the said 45 voids. The fillet plates 30 are flat, and relatively thin, and have outer straight edges 31 and inside edges 32 arranged divergent with respect to the edge 31, and the bottom bevel edge 32^a and the top bevel edge 33. 50 The lower and upper edges 32^a and 33 are beveled at an angle of approximately 45° with respect to the outer edge 31, and at the juncture of the edges 32 and 33 the fillet plate or piece 30 is notched or removed at 55 36 to conform to the shape of the lower edge of the drop siding pieces upon which the guard or weather stripping construction may be applied.

The application of the fillet plates 30 is 60 apparent from Figures 2 and 6 of the drawing. The notch 36 fits against the projecting margin or edge of the drop siding, with the edge 32 arranged in abutment against the outer sloping face of the drop siding, and it 65 is to be noted that the upper and lower edges

33 and 32^a respectively of the fillet plate slope downwardly at an angle of approximately 45° away from the drop siding. The fillet plates 30 are arranged in aligning relation along the edge of the finishing or casing piece F, and secured thereto by nails 40; the fillets being provided with openings 41 to receive said nails, which are driven into the siding F. The fillet pieces 30 thus seal the openings to the voids between the casing 70 piece F and the drop siding, and it is apparent that due to the individual provision of the fillets they may be adjusted to suit the application of the drop siding in its overlapping relation. To illustrate how important is the individual provision of the fillets, in Figures 2 and 6 it is shown that certain drop siding strips are not closely fitted together, and provide spaces 50. The fillets may be arranged to seal the voids and 75 this leaves a space 51, such as shown in Figures 2 and 6 of the drawing, at the outermost edge along the drop siding, where the same will not interfere with the complete sealing of the voids. However, this recess or space 51 is later sealed by the application 80 of the border sealing strip 55. The width of the fillet pieces 30 is such that when applied the vertical edges 31 align with each 85 other, as shown in Figures 2 and 6 of the drawing, and do not completely cover the side edge of the finishing or casing piece F.

To finish off the appearance of the guard and weather stripping construction and fillet pieces 30, and afford a more complete 100 seal, the border strip 55 is provided; the same being an elongated continuous piece of material extending thruout the length of the finishing or casing piece F, and overlapping outwardly upon the major portions 105 of the fillet pieces 30, as illustrated in Figures 2, 3 and 6 of the drawing; the said piece 55 having an inner straight edge 60 which abuts against the outermost edges of the face portions of the drop siding. These 110 border pieces 55 have openings 67 therein for receiving nails 68 by means of which the strip 55 may be secured to the remaining exposed edge portion of the finishing or 115 casing piece F, as illustrated in Figures 2, 3 and 6 of the drawing, and it is preferred that the strip 55 be offset so as to abut both 120 against the outer exposed sides of the fillet pieces, and against the exposed edge of the finishing piece F, as shown in Figure 3 of 125 the drawing. Thus the voids between the faces of the drop siding and the finishing or 130 casing pieces F are completely sealed. The only difference between the fillet pieces 30 of the forms of invention G and G' is the 135 fact that divergence between the edges 31 and 32 of these fillet pieces of the different forms may be to a greater or less degree, and the notches or recesses 36 may be differently formed to conform to the contour at 140

the lower edge of the most projected portions of the drop siding, as can readily be understood.

From the foregoing description of this invention it is apparent that an improved guard and weather stripping construction has been provided for use in building construction, which will provide a superior and improved building construction, both from 10 a weather proof standpoint and from the standpoint of sanitation.

Various changes in the shape, size, and arrangement of parts may be made to the form of invention herein shown and described, without departing from the spirit of the invention or the scope of the following claims.

I claim:

1. In building structure the combination 20 of drop siding, an upright finishing or casing strip applied upon the outer side of the drop siding, and a sealing strip to close the voids between the strip and facing side of the drop siding consisting of a thin piece of material attached to the outside edge of the strip and extending across the openings to the voids and having an edge cut to the cross sectional shape as the outside surface of the siding and abutting thereagainst in 30 snug sealing relation therewith.

2. In building structure the combination 35 of drop siding and an upright finishing or casing strip applied upon the outer side of the drop siding, and a plurality of sealing pieces to close the voids between the strip and facing side of the drop siding each 40 consisting of a body portion attached to the outside edge of the strip and extending across an opening to a void and having an edge cut to the cross sectional shape of the adjacent outside surface of the siding and abutting there against in snug and sealing relation, said sealing pieces being arranged 45 along the edge of the strip in conformity to the drop siding to seal all of the openings to the voids.

3. In building structure the combination 50 of drop siding and an upright finishing or casing strip applied upon the outer side of the drop siding, and a plurality of sealing pieces to close the voids between the strip and facing side of the drop siding, each 55 consisting of a body portion attached to the outside edge of the strip and extending across an opening to a void and having an edge cut to the cross sectional shape of the adjacent outside surface of the siding and abutting thereagainst in snug and sealing relation, said sealing pieces being arranged 60 along the edge of the strip in conformity to the drop siding to seal all of the openings to the voids, and a finishing border strip attached to an edge of the finishing or casing strip and being continuous and overlapping all of the individual sealing pieces

and having an edge abutting against the outermost portions of the drop siding.

4. As an article of manufacture guard and weather stripping construction for sealing the voids between drop siding and finishing 70 or casing pieces comprising metal strip means having a saw toothed edge arranged therealong to conform in snug abutment with the conventional overlapped drop siding of building construction, and an elongated continuous border strip for overlapping association with the first mentioned strip. 75

5. As an article of manufacture a thin flat sealing strip for building construction comprising a body having upper and lower edges beveled in angled relation with respect to the length of the body, said body having longitudinal edges arranged in a divergent relation from the lower edge to the upper edge thereof, said body at the 85 juncture of the top edge and one longitudinal edge being notched.

6. In combination with drop siding and upright finishing or casing strips applied upon the outer side of the drop siding, a 90 sealing strip construction secured to an edge of the finishing or casing strip and having a saw toothed edge facing the outer surface of the drop siding in an abutting relation on the outer surface of the drop siding and 95 extending across the openings to the voids between the drop siding and finishing or casing strips to seal the same, said sealing strip construction comprising a plurality of pieces having end edges downwardly sloping away from the drop siding. 100

7. In combination with drop siding and upright finishing or casing strips applied upon the outer side of the drop siding, a sealing strip construction secured to an edge 105 of the finishing or casing strip and having a saw toothed edge facing the outer surface of the drop siding in an abutting relation and shaped to the cross section of the outer surface of the drop siding and extending 110 across the openings to the voids between the drop siding and finishing or casing strips to seal the same, said sealing strip construction comprising a plurality of pieces providing edges downwardly sloping away from 115 the drop siding, and a continuous border strip applied to the edge of the finishing or casing strip and overlapping the outer sides of the sealing strip construction above described. 120

8. In combination with drop siding, finishing or casing pieces applied to the drop siding of conventional construction, a plurality 125 of sealing strips attached to the finishing or casing strips and shaped at edges facing the drop siding into conformity to the cross sectional shape of the outer surface of the siding and extending across the openings to the voids beneath the adjacent finishing or casing strip, to seal said voids, said sealing 130

strips extending across part only of the edge of the finishing or casing strip to which attached, and a continuous border strip attached to the exposed portion of the finishing or casing strip and having a part overlapping upon the sealing strips.

9. In a building construction the combination of drop siding and finishing or casing strips of conventional construction attached thereto, fillet pieces of sheet metal

attached to one edge of the finishing or casing piece, said fillets being shaped to conform to the cross sectional shape of the outside surface of the drop siding and engaging in snug abutment thereagainst to seal the void openings between the siding and strip, and a continuous border piece attached to the edge of the siding over said fillets.

MICHAEL MULLINS.
